UNITED STATES PATENT OFFICE

AVERY A. MATHESON, OF BINGHAMTON, NEW YORK, ASSIGNOR TO AGFA ANSCO CORPORATION, OF BINGHAMTON, NEW YORK, A CORPORATION OF NEW YORK

MERCHANTISING AND DISPLAY RECEPTACLE

Application filed March 16, 1931. Serial No. 522,824.

My invention relates generally to receptacles and particularly to the type used for displaying, dispensing, and transportation of articles of merchandise and is especially adaptable to articles such as photographic film.

I have provided a suitable container in which a representative assortment of sizes or kinds of articles may be segregately classified and indexed according to sizes. This container is strong and durable and so designed that it may be wrapped and sent through the mail or other means of transportation to the dealers.

15 The dealer upon receiving my improved package merely has to unwrap it and set it in a convenient place in the store and dispense the articles directly from it as the occasion requires.

20 The receptacle is so designed as to be attractive and decorative and aside from the convenience in transportation and merchandising of the articles, forms a rather effective and unique advertising item for the store.

25 One particular feature of my improved receptacle lies in a novel arrangement whereby a complete new setup of articles is stored ready for use and is made available for dispensing in the usual manner, by merely reversing the position of the cover with respect

30 to the body portion of the container. This feature is of particular importance and proves to be especially advantageous in merchandising articles of this character for, if 35 through oversight or negligence the dealer permits his supply of stock to become depleted without placing an advance order for replenishing same, he has immediately available this second or reserve supply thus eliminating the occurrence of being "sold out".

Specific objects and advantages in details of construction will be apparent as the description proceeds, reference now being had to the figures of the accompanying drawing

45 forming a part of this application and wherein like reference numerals indicate like parts.

While I have described and illustrated my invention in connection with photographic film, it will, of course, be understood that it

50 is readily adaptable to many other articles

of merchandise and that this description and the drawing are to be taken as illustrative only.

In the drawing:

Figure 1 is a perspective view of my improved receptacle taken from the front thereof. 55

Figure 2 is a perspective view taken from the rear thereof, certain parts being broken away for clearness. 60

Figure 3 is a sectional plan view of same.

Figure 4 is a perspective view of the receptacle with the cover raised preparatory to re-positioning same on the body thereof. 65

The receptacle is preferably constructed of heavy cardboard material but may be equally as well formed of light metal material or the like.

The reference numeral 1 refers to a box like structure 1 over which there is adapted to be placed the usual cover 2 comprising the top 3, end walls 4, front 6, and back 7 respectively. This cover 2 is preferably formed so as to completely encase the box 1 with the exception of the side 7 which is preferably formed so as to fall short of completely covering the back of the receptacle in order that the film cartons or other articles 8 may be withdrawn one at a time from the bottom thereof. 70

The sides of the box 1 lying adjacent the front and back sides 6 and 7 of the cover 2 are open and have suitably provided therein partitions or separators 9 of suitable varying lengths and widths to accommodate the articles placed therein in rows or stacks as clearly shown in Figures 2 and 4, the backings 10 of such partitions being formed substantially in step formation as clearly shown in Figure 3, thus permitting articles of varying lengths and widths to be stacked in the carton or container with their front ends flush with the inner surfaces of the sides 6 and 7 of the receptacle. 85

The lower ends of these partition members 9 are formed preferably with cut out portions 11 thus permitting the taking hold of the lowermost article in each compartment for removal therefrom. The end walls 4 of the 90

100

cover are similarly cut away as at 12 for the same purpose. It is understood, of course, that when using the receptacle as a dispenser, the pulling out of the lowermost article in any compartment results in the lowering of the next article above to the position occupied by that one removed. In this manner, clean fresh stock is always available and such arrangement is especially valuable in connection with film as the same can be dispensed in accordance with its age, that is the older stock being the first taken out.

The dealer when displaying the receptacle in the store preferably sets same on the counter or cabinet so that the front side 6 of the cover is facing the customers and the rear side 7 from which the articles are removed, directly away from same. In this position any advertising matter which may be and preferably is printed on the cover 2 (particularly the front 6) may easily and readily be observed. It is obvious that when the articles contained in one side of the box 1 have been completely dispensed the dealer merely removes the cover 2 therefrom, reverses the position of the box 1 and replaces the cover 2 thereon, thus bringing into dispensing position a completely new set up of film cartridges or other articles which are stacked therein.

It will be observed from the foregoing that my improved receptacle is not only especially useful as a dispensing and reserve supply storage unit but also provides a substantial, economical carton or package for shipping the merchandise contained therein, and which can be used immediately as a dispenser and advertising unit without the unnecessary handling of the contents.

Of course, changes may be made in details of construction and arrangement of parts without departing from the spirit and scope of my invention. I do not limit myself therefore to the exact form herein shown and described other than by the appended claims.

I claim:

1. A receptacle comprising a box having open front and rear sides, partition members in said box forming a plurality of compartments opening on both sides of the box, and a removable cover member adapted to close either side of said box entirely, the lower edge of one side only of said cover terminating slightly above the bottom of said box, permitting access to the compartments at the lower edge of one side of said box.

2. A receptacle comprising a box having open front and rear sides, partition members in said box forming compartments opening on both sides of said box, and a removable and reversible cover member having one side of substantially the same height of the box whereby to completely cover the side of the box adjacent thereto and the opposite side terminating slightly above the bottom of the

box, permitting access to the compartments only at the lower edge of the side of said box adjacent thereto.

In testimony whereof, I affix my signature.

AVERY A. MATHESON.
